DESIGN FOR A BELT BUCKLE

Clarence E. Beatty, Colorado Springs, Colo.

Application September 2, 1944, Serial No. 115,176

Term of patent 14 years

(Cl. D17—1)

To all whom it may concern:

Be it known that I, Clarence E. Beatty, a citizen of the United States, residing in the city of Colorado Springs, county of El Paso, and State of Colorado, have invented a new, original, and ornamental Design for Belt Buckle, of which the following is a specification, reference being had to the accompanying drawing, forming part thereof.

In the drawing:

Figure 1 is a top plan view of a belt buckle showing my new design; and

Figure 2 is a side elevation thereof.

I claim:

The ornamental design for a belt buckle, as shown.

CLARENCE E. BEATTY.
